Patented Feb. 18, 1919.

UNITED STATES PATENT OFFICE.

GEORGE DENMAN AND EDWARD F. LEWIS, OF TERRE HAUTE, INDIANA.

FUSE.

1,294,880.

Specification of Letters Patent.

Patented Feb. 18, 1919.

Application filed March 27, 1918. Serial No. 224,952.

To all whom it may concern:

Be it known that we, GEORGE DENMAN and EDWARD F. LEWIS, citizens of the United States, and residents of Terre Haute, in the 5 county of Vigo and State of Indiana, have made certain new and useful Improvements in Fuses, of which the following is a specification.

Our invention is an improvement in fuses 10 and has for its object to provide a fuse consisting of a primary and auxiliary fuse so arranged in the circuit that when the primary fuse is burned out, the current will be automatically transferred to the secondary 15 auxiliary fuse, without any interruption to the service.

In the drawing:

Figure 1 is a front view of the improved 20 fuse,

Fig. 2 is a section on the line 2—2 of Fig. 1, looking in the direction of the arrows adjacent to the line, and

Fig. 3 is a sectional view of the primary 25 fuse.

In the present embodiment of the invention a suitable base 1 is provided upon which the fuses are mounted, the secondary or auxiliary fuse 2 being of the usual or ordinary construction, and being held on the base by 30 the usual clips 3.

The primary fuse consists of a cylindrical body 4, having a cap 5 at its lower end, and having a sleeve 6 at its upper end, the said 35 sleeve being of conducting material, and the upper end of the sleeve is flush with the upper end of the body 4.

A cap 7 is provided for covering the top 40 of the body and the sleeve, the cap fitting around the body and sleeve, and it will be noticed that the body, the sleeve and the cap 7 have registering openings at the top of the sleeve and body, for permitting access to mechanism to be later described arranged within the casing for the fuse.

Holding clips 8 and 9 are provided for 45 the casing, and the clip 8 is at the sleeve 6, and engages said sleeve as shown. The clip 9 is at the cap 5 and engages the cap, and a contact plate 10 is arranged on the base at 50 the clip 8, the said plate being connected to the clip and the sleeve 6.

The lead wire 11 from the primary line is 55 connected with a binding post 12 on the plate, and a switch lever 13 is hinged to the plate, as indicated at 14. A pair of spring contact plates 15 is arranged above the piv-

otal connection 14 of the switch lever and the switch lever 13 is adapted to engage the contact plates to connect the primary lead wire 11 to a lead wire 16, which passes from 60 the contact plates 15 to the secondary fuse 2. The lead wire 17 to the transformer passes from a binding post 18 connected to the clip 3 and a lead wire 19 connects the clip 9 of the primary fuse with the clip 3 65 of the secondary or auxiliary fuse.

The fuse 20 of the primary fuse is connected at its upper end to a depending lug 21 on the cap, by means of a screw 22, which is accessible through the registering openings, before mentioned, in the cap, sleeve and body. The lower end of the fuse 20 is connected to a binding post 23 on a lug 24 depending from the cap 5 and the fuse 20 is inclosed by a tube 25 of insulating material, 75 as for instance, fiber.

The cap 7 is movable on the sleeve and this cap is normally pressed upward by a coil spring 26 arranged within the fuse casing between the cap 7 and a stop 27 in the 80 form of a collar on the tube 25. A contact plate 28 is secured to the base above the cap 7, and in position to be engaged thereby, when the cap is moved upward by the spring under conditions to be later mentioned, and 85 this contact plate is connected with the lead wire 16.

In operation under ordinary conditions the current passes by way of lead wire 11, the contact plate 10, the sleeve 6 and the cap 90 7, through the fuse 20 and by way of the lead wires 19 and 17 to the transformer. Should the fuse 25 burn out, the cap 7 will be no longer restrained, and the spring 26 will force the cap up into contact with the 95 plate 28. The current now passes from the lead wire 11 by way of the sleeve 6, and the cap 8 to the contact plate 28, and by way of the lead wire 16 through the secondary fuse, so that the service is not interrupted.

When it is desired to replace the primary fuse, the switch lever is turned upward into contact with the plates 15 and the current now passes directly from the primary line through the secondary auxiliary fuse, and the primary fuse is cut out of the circuit. When the fuse wire 20 has been inserted and is connected with the binding post 23 at its lower end, the cap is depressed and the upper end of the fuse wire is connected to the 110 lever 21, and the fuse then holds the spring under compression. The switch lever 13 is

2
now moved in the position of Fig. 1, and the fuse is again ready for operation.

It will be understood that the fuses may be made in any carrying capacity to meet all requirements, and the spring will be made to correspond with the size of fuse wire used. When trouble develops in the transformer, and has been corrected and the transformer is ready to be put back into service, it may be tested without danger by simply moving the primary fuse and using a fuse of small capacity in place of the auxiliary fuse. With the switch 13—15, the current may be passed through the said fuse, and in case there is still trouble in the transformer, the small fuse will blow.

It will be understood that in placing the fuse wire 20 it is first connected with the binding post 22.

20 We claim:

1. A device of the character specified, comprising a primary and a secondary fuse, the primary fuse having at each end a cap, and the cap at the upper end being movable, 25 a spring normally pressing the cap upward, a fuse wire arranged between the caps and normally holding the spring under compression, a contact plate arranged above the primary fuse and in position to be engaged by the cap when it is forced upward by the spring, a lead wire connected to the plate and to one end of the secondary fuse, a lead wire connected with the lower cap of the primary fuse and with the other end of the 30 secondary fuse, a conducting sleeve on the primary fuse upon which the movable cap moves, the line wire being connected with the said sleeve and a switch for connecting the line wire directly with the lead wire of 35 the contact plate.

2. A device of the character specified comprising a primary and a secondary fuse, said primary fuse comprising a casing, having a movable cap at its upper end to which the 45 fuse wire is connected, a spring normally forcing the cap upward, a fuse wire holding

the spring under compression, the primary fuse being interposed in the line wire, a contact plate above the movable cap and adapted to be engaged thereby when the cap 50 is moved upward by the spring, and a connection between the plate and the secondary fuse for interposing the secondary fuse in the line wire when the cap engages the plate, and means for cutting out the primary fuse 55 from the line wire and for cutting in the secondary fuse.

3. A device of the character specified comprising a primary and a secondary fuse, said primary fuse comprising a casing, having a 60 movable cap at its upper end to which the fuse wire is connected, a spring normally forcing the cap upward, a fuse wire holding the spring under compression, the primary fuse being interposed in the line wire, a contact plate above the movable cap and adapted to be engaged thereby when the cap 65 is moved upward by the spring, and a connection between the plate and the secondary fuse for interposing the secondary fuse in 70 the line wire when the cap engages the plate.

4. A device of the character specified comprising a primary and a secondary fuse, connections between the corresponding terminals at the ends of the fuses, the end of one fuse being adapted for connection with one terminal of a line and the other end of the other fuse with the other terminal of the said line, one of the said connections between the ends of the fuses being normally interrupted, a movable portion on the primary fuse for closing the said connection and normally held by the fuse out of engaging position, and a spring pressing the movable portion in a direction to close the said connection. 75 80 85
